FIG. 2.

INVENTOR.

JOHN E. CRADDOCK

BY

John J. Lynch

ATTORNEY.

UNITED STATES PATENT OFFICE

110,714

DESIGN FOR A BALL GAME DEVICE

John E. Craddock, Coney Island, N. Y.

Application December 3, 1937, Serial No. 73,336

Term of patent 14 years

To all whom it may concern:

Be it known that I, John E. Craddock, a citizen of the United States, residing at Coney Island, county of Kings, and State of New York, have invented a new, original, and ornamental Design for a Ball Game Device, of which the following is a specification, reference being had to the accompanying drawing, forming a part thereof.

In the drawing:

Figure 1 is a view in side elevation of my new design of ball game device, and

Figure 2 is a view in front elevation of the new design of ball game device illustrated in Figure 1.

I claim:

The ornamental design for a ball game device, as shown.

JOHN E. CRADDOCK.
